ATTORNEY

UNITED STATES PATENT OFFICE

AMOS E. TULLIS, OF MINNEAPOLIS, MINNESOTA

ARTIFICIAL LIMB

Application filed December 15, 1931. Serial No. 581,208.

This invention relates to artificial limbs.

An object of the invention is the provision of an artificial limb having a plurality of air cushions so placed that they will take up the irregularities in the amputated member to provide a yielding supporting surface for said amputated limb.

A further object of the invention is the provision of an artificial limb having a socket portion provided with a plurality of passages in the side walls thereof and an annular groove located externally of the socket, said socket being received by a shell, an elastic tube received within the groove and adapted to be inflated for forcing the tube through the openings to provide cushions at particular points in the socket for aiding in comfortably supporting an amputated member.

This invention will be best understood from a consideration of the following detailed description, in view of the accompanying drawing forming a part of the specification; nevertheless, it is to be understood that the invention is not confined to the disclosure, being susceptible of such changes and modifications which shall define no material departure from the salient features of the invention as expressed in the appended claims.

In the drawing:

30 Figure 1 is a view in elevation of an artificial limb constructed in accordance with the principles of my invention,

Figure 2 is a vertical section taken along the line 2—2 of Figure 3, and

35 Figure 3 is a top plan view of the socket shown in Fig. 1 with parts broken away.

Referring more particularly to the drawing, 10 designates a substantially rigid body portion of an artificial limb which has a shell 11 surrounding the same and secured thereto, as shown in Fig. 2. A socket, generally designated by the numeral 12, which is adapted to receive the amputated portion of a limb, rests upon the upper end 13 of the hollow body portion 10.

The socket is provided with a plurality of spaced openings 14 at predetermined points in the socket for a purpose which will be presently explained. An annular groove 15 entirely

the openings 14 so that a peripheral portion 16 of the openings 14 will be slightly thinner than the body portion of the socket 12. An inner liner in the form of a sleeve 20 is suspended from the upper end of the socket 12 and projects loosely into the socket and projects partially into the upper end of the hollow body portion 10 of the artificial limb. The liner at its upper end is provided with a flange 21 located exteriorly of the socket and is disposed between the shell 11 and the outer wall of the socket. The liner is made of flexible material such as fabric or it may be made of any form of elastic material, such as rubber, if desired.

An endless elastic tube 25 is located within the annular groove 15. This tube may be made of any material such as rubber which will permit portions of the tube to expand when filled with air in order to force the portions of the tube through the openings 14 to provide air cushions as indicated at 26. A tube 27 formed of any hard material is connected with an opening in the tubular member 25 and is provided with the usual valve to permit the tube 25 to be filled with air in any well known manner. A liner 30 formed of fabric is mounted in the groove 15 and embraces the inner face of the tube 25. The liner is so constructed that it will be forced through the openings 14 when the proper amount of air has been supplied to the annular tube 25. A second liner 32 embraces the outer face of the annular tube 25 and flatly contacts with the inner wall of the shell 11. The liners are held in place in any approved manner within the socket 12.

The amputated member is placed within the socket 12 and received by the fabricated sleeve 20, after which air is supplied through the feed 27 until the portions of the annular air tube 25 have moved through the openings 14 in the socket 12 for engaging and supporting the amputated member. At this time the liner 30 is moved inwardly through said openings and in engagement with the sleeve 20.

I claim:

1. An artificial limb comprising a substantially rigid socket member having openings

50 circles the exterior of the socket and spans

- in the side walls thereof, a shell embracing said socket, a liner formed of flexible material suspended within the socket, an elastic tube located between the outer wall of the socket and the shell, valve means through which air may be forced for inflating the tube so that the portion of the tube within the openings will be inflated and provide cushioning means for the amputated member.

2. An artificial limb comprising a substantially rigid socket member having openings in the side walls thereof, a shell embracing said socket, a liner formed of flexible material suspended within the socket, an elastic tube located between the outer wall of the socket and the shell, valve means through which air may be forced for inflating the tube so that the portion of the tube within the openings will be inflated and provide cushioning means for the amputated member, a second liner located between the inner wall of the elastic tube and the outer wall of the socket.

3. An artificial limb comprising a substantially rigid socket member having openings in the side walls thereof, a shell embracing said socket, a liner formed of flexible material suspended within the socket, an elastic tube located between the outer wall of the socket and the shell, the inner face of the tube adjacent the openings being unsupported, valve means through which air may be forced for inflating the tube so that the portions of the tube opposite the openings will project inwardly through the openings and form cushioning means for an amputated member.

4. An artificial limb comprising a substantially rigid socket member having openings in the side walls thereof, a shell embracing said socket, a liner formed of flexible material suspended within the socket, an endless elastic tube located between the outer wall of the socket and the shell, valve means through which air may be forced for inflating the tube so that the portion of the tube within the openings will be inflated and provide cushioning means for the amputated member, the outer wall of the socket being provided with an annular groove to receive the annular elastic tube.

5. An artificial limb comprising a substantially rigid socket member having openings in the side walls thereof, a shell embracing said socket, a liner formed of flexible material suspended within the socket, an endless elastic tube located between the outer wall of the socket and the shell, valve means through which air may be forced for inflating the tube so that the portion of the tube within the openings will be inflated and provide cushioning means for the amputated member, the outer wall of the socket being provided with an annular groove to receive the annular elastic tube, and a liner located exteriorly of the tube and held in place by the shell.
